UNITED STATES PATENT OFFICE.

WILLIAM HEWITT, OF CHAMBERSBURG, ASSIGNOR TO THE TRENTON IRON COMPANY, OF TRENTON, NEW JERSEY.

WIRE BALE-TIE.

SPECIFICATION forming part of Letters Patent No. 381,071, dated April 10, 1888.

Application filed November 30, 1887. Serial No. 256,497. (No model.)

To all whom it may concern:

Be it known that I, WILLIAM HEWITT, a citizen of the United States, residing at Chambersburg, Mercer county, State of New Jersey, have invented an Improvement in Wire Bale Ties, of which the following is a specification.

My invention relates to a class of devices in which the bale band proper is composed of wire and in which the fastening device proper is a locking head composed of an independent piece of metal and not formed of the wire of the bale band proper.

It further relates to a class of devices in which the locking head is composed essentially of a hook and brace and is adapted to be engaged with a free loop formed upon the opposite extremity of the bale band proper to that to which said head is applied.

The bale tie which I have devised comprehends a wire band formed with a closed, and more or less elongated, loop at each of its extremities,—the loops being respectively formed by bending back each extremity of the wire and twisting the end of the bent back portion around or with the main stem,—and provided with an independently formed and applied locking head formed of a properly shaped blank of sheet metal folded upon itself about or around one side or lateral portion of one of the loops, which I term the head loop, of the band, with which loop the head is thereby rigidly engaged. The locking head when applied presents the appearance of one half of an arrow head applied to one extremity of the wire band,—the general appearance being substantially such as would be presented by an arrow head applied to the end of a rod or shaft and then cut in halves along its median line and deprived of one half of its substance. The locking head is, moreover, intentionally applied to one side or lateral portion of one of the elongated loops, namely, the head loop, in such manner that both sides or lateral portions of said loop and the web portion of the head proper occupy the same plane. The barb or base of the locking head constitutes a hook and its pointed extremal portion or apex, which projects beyond the rounded closed end of the head loop, constitutes a brace. The

wire band, which I term the free loop, preferably in its formation upon the wire band, occupies a plane right angular to the plane occupied by the head loop, and is adapted to be engaged with the locking head of said head loop by being slipped over the head at an angle and then straightened into line with the axis of the head loop;—in which position engagement of the closed outer extremity of the free loop is effected by the hook or barb of the locking head, while the brace bears upon the inner, or twist-closed, extremity of said free loop and serves to retain the latter in place when strain is exerted upon the band as an entirety.

In the accompanying drawings I have represented a preferred and a modified construction of bale tie alike embodying my invention, and in this specification I describe both of said constructions, while the particular subject matter which I claim as novel is hereinafter definitely specified.

In the drawings, Figure 1 is a side elevational view of a bale tie embodying my invention. Fig. 2 is a perspective fragmentary detail of the same, illustrating the position of the locking parts in the act of being engaged. Fig. 3 is a similar view of the same parts when engaged. Fig. 4 is a view in side elevation but otherwise corresponding to Fig. 3. Fig. 5 is a plan view of the blank from which the locking head represented in Figs. 1, 2, 3, and 4, is formed. Figs. 6, 7, and 8 are perspective views from different standpoints of the locking head represented in said Figs. 1, 2, 3, and 4. Fig. 9 is a view of a modified form of blank from which to make such a modified form of locking head as is represented in Figs. 10 and 11. Fig. 10 is a top plan view and Fig. 11 a side elevational view of a tie provided with the modified form of locking head referred to, in the position which its parts occupy when engaged.

Similar letters of reference indicate corresponding parts.

In the drawings, B represents the wire comprising the bale band proper.

b is a free loop formed, as shown, at one extremity of the band proper.

b^x is a head loop formed, as shown, at the opposite extremity of the band proper.

The head loop and the free loop are preferably formed upon the wire of the band in relatively right angular planes.

A is the locking head, which is connected with the head loop of the band. This locking head is preferably made from a blank of sheet metal of the form shown in Fig. 5, that is to say, of a blank composed of two counterpart wing portions *a a* connected by a neck or web 10 the length of which is preferably slightly less than the length of the interior opening of the head loop. The completed locking head is formed by folding together the counterpart wings of the head blank and in so doing folding their connecting web or neck to form a tubular sleeve *a'*, as shown in Figs. 1, 2, 3, 4, 15 6, 7, 8, and 11, which incloses one side or lateral portion of the head loop.

The application of the head blank to form 20 the locking head may be made after the head loop is completely formed, the two wings of the head blank being subjected to pressure in a die or press, or by means of a suitable special tool; or the locking head itself may be independently formed from the blank or be cast 25 as an entirety, and the head loop formed after the free extremity of that end of the wire of the band which is formed into said head loop has been passed through the bore of the tubular sleeve of the completely formed locking 30 head.

The locking head when completed presents a hook *c* constituted by its rear face, and a brace *d* constituted by the inside faces of the 35 extended or forwardly-projecting portions of the wings of the head blank.

In Figs. 9, 10, and 11, I have represented a blank in which the forwardly-projecting portion of one of the wings of the head blank is

cut away as shown in Fig. 9, the result, when 40 said blank is bent up, being the production of a locking head such as is shown complete in Figs. 10 and 11, which is to all intents and purposes the same locking head as that shown in the preceding figures of the drawings, al- 45 though its brace is of but single thickness.

Having thus described my invention, I claim:—

1. In combination with a loop formed at one end of a wire composing the band of a wire 50 bale tie, an independently formed metal locking head possessing a hook and a brace and engaged with and secured to one side or lateral member of said loop.

2. In a wire bale tie, the combination of a 55 wire band formed with a closed loop at each of its ends, with an independently formed and applied metal locking head possessing a hook, a brace, and a hollow sleeve through which one side or lateral portion of one of the loops 60 of the wire band passes in order to effect the attachment of said head, substantially as set forth.

3. In a wire bale tie, the combination of a 65 wire band formed with a closed loop at each of its ends, with an independently formed and applied locking head composed of a blank of metal possessing wing portions connected by a web or neck portion, and engaged with one of the loops of the wire band by being folded 70 as to its neck portion about one side or lateral portion of said loop, substantially as set forth.

In testimony whereof I have hereunto signed my name this 28th day of November A.D. 1887.

WM. HEWITT.

In presence of—

J. BONSALL TAYLOR,
WM. C. STRAWBRIDGE.
